UNITED STATES PATENT OFFICE.

JOHN Q. SHERMAN, OF DAYTON, OHIO.

MANIFOLDING TYPEWRITER.

Application filed August 11, 1920. Serial No. 402,753.

To all whom it may concern:

Be it known that I, JOHN Q. SHERMAN, a citizen of the United States, and a resident of the city of Dayton, in the county of 5 Montgomery and State of Ohio, have invented certain new and useful Improvements in Manifolding Typewriters, of which the following is a full, clear, and exact description, reference being had to the drawings accompanying this specification.

My invention relates to manifolding typewriters, particularly adapted for making a large number of copies on continuous webs of paper.

15 One of the great difficulties in connection with the making of a plurality of copies of the same typewriter impression on the usual form of typewriting machine wherein the type operating devices are stationary and 20 the platen movable, is that to provide continuous webs of paper has required the moving of a large bulk of paper along with the carriage of the machine. It is one of the main objects of my invention herein, to provide for a stationary roll rack for the various webs of paper, and arrange for the maintenance of a sufficient loop of paper between the roll mounting rack and the typewriter carriage to permit of the carriage 25 movement without resulting in straightening out the loop, the loop being sufficiently long to permit the typewriter carriage to move back and forth the full length of its 30 normal feed without tearing the paper webs.

35 In connection with my machine I also provide for a rewind roll to retain one of the webs of paper in the machine as a record and means for maintaining lateral alignment of the paper webs.

40 The feeding mechanism for the paper is of the type wherein rotating pin bearing bodies successively enter spaced holes in the paper, and while feeding the paper, act to jog the webs thereof into line, thereby maintaining longitudinal alignment as well as feeding the paper past a point for reception of type impressions against a platen.

45 I also provide for the mounting of carbon paper for use between the various films or webs, thereby providing for the transfer of type impressions, and I preferably combine this carbon paper mounting with the means for maintaining lateral alignment of the paper films.

55 I also provide for various other improve-

ments and additions for manifolding typewriters which will be brought out in the following matter and generally I accomplish my various objects by that certain construction and arrangement of parts to be herein-after more specifically pointed out and claimed.

In the drawings,

Figure 1 is a perspective view of my new device.

Figure 2 is a side elevation of the operating device for the rewind roll.

Figure 3 is a detail plan view of the loop forming feed device.

Figure 4 is a detail side elevation of the storage rack and the feed pin wheels.

Figure 5 is a detail front elevation of the typewriter platen and the rewind devices.

Figure 6 is a detail perspective of the platen shaft and a broken away portion of the platen.

Figure 7 is a detail elevation of the loop feed operating sprocket which is mounted on the platen shaft.

Figure 8 is a detail front elevation of the lateral aligning devices and the carbon paper mounting.

Figure 9 is a side elevation of the parts shown in Figure 8.

Figure 10 is a more or less diagrammatic section, showing a means for guiding the paper around the printing platen without friction.

Figure 11 is a fragmentary perspective view of the same parts.

Figure 12 is an elevation of the pawl controlling slide for the carbon paper advancing mechanism.

Figure 13 is a top plan view of the carbon paper advancing mechanism.

Figure 14 is a dis-assembled view of the telescoping arm.

Figure 15 is a side elevation of the carbon paper advancing mechanism and paper clamp.

Figure 16 is a detail elevation of the pawl.

Figure 17 is a front plan view of the friction roll device of the carbon paper mechanism. Figure 18 is a detail front and side view of a modified pressure device. Figure 19 shows a paper roll spindle.

The machine is shown, for purposes of illustration as having a fixed frame 1 on which rides the usual typewriter carriage 2, bearing the rotatable platen 3. It will be

understood that the typewriter itself, with the exception of the additional feeding devices to be described, is the same as any ordinary typewriter and may vary with the 5 design of typewriter which it is desired to employ.

There will be also any desired form of paper storage frame 4, which is likewise stationary, and carries a rack 5, in which are 10 set the desired number of rolls of paper 6, on spindle 6^a.

The roll mounting should be such as to permit fairly free rotation of the rolls 6, and the webs of paper are preferably 15 brought up from the rolls and thence over spaced idler rolls 7, which separate the webs from each other and give to each web an independent path, so that it can travel free of friction, particularly when turning at any 20 angle.

The usual form of paper employed in connection with my machine will be webs printed up into corresponding forms upon which it is important that the impressions made 25 on each form shall correspond as to position on the form, to all impressions on the remaining forms. The paper has on one or both margins a series of interspaced holes, punched with uniform relation to the printed matter on the forms, so that when the 30 holes are aligned the printed matter will be aligned also. For convenience the top most web of paper as it passes through the machine is indicated as A, and the bottom 35 sheet as B. The spaced holes are indicated as C.

As will be noted I employ the same set of marginal holes for both lateral and longitudinal alignment of the paper webs, and 40 for the feeding of the webs to form the loop, hitherto noted.

Following the paper webs in their path from the storage to the printing point and the record rewind, after they pass over the 45 idler rolls, they are engaged by a feeding device. This device comprises preferably a shaft 8, on which is mounted a pair of pin bearing wheels 9, said wheels preferably having a groove 10, at the outer side thereof.

50 A stripper plate 11 extends from the mounting pin 12 thereof, over the top of the shaft 8 and wheels 9, the outer ends of the plate being adapted to lie in the grooves 10 in the pin wheels and the plates 55 being slotted to clear the pins.

The pins 13 on the wheels are arranged to engage in successive holes of the desired 60 number of superimposed paper webs, and the webs are kept down on the pins by means of a roller 14, having pin clearance slots 15, and held on arms 16. A spring controlled 65 shaft 17 serves as the mounting member for the arms, and the roller may be held out of operation by a latch 18. As will be observed the roller engages the rib 19 at the

outer ends of the pin wheels, thereby keeping it from frictional contact with the paper, and permitting the free automatic adjustment of the various webs as they are fed by 70 said pin wheels.

The platen 3 of the typewriter carriage is mounted on a splined or a flattened shaft 20, which extends considerably beyond the platen and the carriage itself, but is carried and revolved in the carriage in the 75 usual manner for a platen shaft.

In a small bracket 21 at the side of the typewriter frame, and held rotatably but otherwise stationary is a sprocket 22. The flattened or splined shaft engages slidably 80 but non-rotatably within this sprocket and rotates it in the same manner that the platen is rotated. The shaft is long enough to extend through and operate the sprocket in all possible positions of the typewriter carriage. 85 Any other well known means of accomplishing this result may be adopted. The above paragraph refers to a preferred means of providing for rotation of the fixed sprocket.

Secured to the frame 4 is a sprocket 23, which is engaged and operated by means of a suitable chain 24, passing over the sprocket 22. A gear or pinion 25 on the same pintle with the sprocket 23 engages a like pinion 26 on the end of the shaft 8, thereby imparting rotation to the pin wheels and feeding the various webs of paper. 90

The mechanism, now described has been termed by me, as the loop feeding or loop maintaining means, since it maintains between the typewriter carriage and the storage frame, a loop of paper, as at D, which permits of a movable carriage and a fixed storage frame, without disturbing the uniformity of feed of the webs of paper to the 100 printing devices.

The frame 4 will preferably be extended forwardly until fairly adjacent to the typewriter frame, and may be walled up (Figure 4) so as to form an enclosed paper storage and loop-containing cabinet. The typewriter carriage may also have extensions 110 27 thereon which act to retain the paper loop in shape, by a loose lateral confinement. The use of a feed of paper to the loop as well as from the loop permits of a compact enclosure and one which protects the loop completely. 115

After passing the loop form the paper is preferably next brought into line laterally by means of a series of idler pin bearing bodies, which likewise act as spacers to prevent binding of the paper webs at the turning point in their path to the platen. 120

A frame 28 is provided, which is secured to the typewriter carriage by means of 125 clamping bolts 29, so that its angle may be adjusted, although this is not a requisite, except that the angle should be such as to provide a separate path for the various webs.

As illustrated washer plates 30 are pro- 130

vided which are mounted on pintles 31, that themselves are journaled in the frame 28, and carry spring 32, inside of the frame to press the washers inwardly. Carbon paper 5 rolls 33, having suitable cores are set over suitable pins or lugs on the inside of the washer plates and are thus held in position. It is not necessary that a spring washer be provided at each side of the frame, and I 10 have thus shown the one side thereof as equipped with pin bolts 34 having their tips entering the carbon paper roll. The pintles 31 are movable to permit removal of the carbon paper rolls, and are preferably knurled 15 for purposes of easy manipulation.

Mounted over the pintles or pin bolts are idler sprockets 35 having hubs 35^a, and of the type generally known as "pin wheel" which have the pins thereon arranged to engage in 20 successive holes in the webs of paper.

I have found that in forming up various multiple printed webs of paper with like printing and arrangement, that it is not practically possible to sever the wide printed 25 webs into separate strips with exact uniformity with relation to the margins of paper extending beyond the printed portion of the webs. The paper slitters cut equal width strips but they shift laterally so that the 30 printing is not uniform with relation to the body of the strip.

It is for this reason mainly that I employ pin wheels engaging in marginal holes in the paper for lateral alignment, since holes can 35 be punched with uniformity to the printing on the paper whereas the slitting into webs cannot be made accurate.

It will be noted that the carbon paper is set between the various webs and held 40 against movement by the spring washer arrangement, now described, and that the carbon paper is of less width than the lateral spacing of the marginal holes to enable it to pass between the pin wheels to the writing 45 point. In order to bring fresh carbon paper at the printing point I provide a special device to be described or else the operator may hold the paper against the platen at the printing point and draw along 50 the carbon sheets together with the films of regular paper.

Suitable gravity rolls 36, set in slots in the frame 28, rest in position to keep the webs of paper down on the idler pin wheels, with- 55 out friction, being properly spaced from the pin bearing bodies for free passage of paper, and stripper plates 37, mounted at the rear side of the idler pin wheels, and extending over the top of the wheels as well as across 60 from side to side of the frame, serve to hold the paper away from the carbon rolls and lift it from the pins.

By provision of a separate lateral alignment pin wheel device for each web of paper, 65 I individualize the films, to the extent of

preventing unequal action on them, and frictional contact between them. As in the case of all rolls to keep the webs of paper down on the pins, I can substitute bars or fingers with like effect, and do not insist in 70 any respect upon fidelity to detail in the construction of machines according to my invention, as per my description herein, which is merely illustrative of a practical working machine of my preferred construc- 75 tion.

After leaving the carbon paper and lateral alignment frame the paper passes, together with the carbon paper, down and around the platen, there being, preferably, suitable 80 guides 57, 58, engaging the paper to prevent its contact with the surface of the platen except at the printing point.

On the ends of the platen are formed suitable pin wheels 38, the pins of which engage 85 in successive holes in the paper webs and draw them along step by step during the operation of the typewriter.

The pin wheels are alike to those described for the loop feeding device, and a like spring 90 roller device 40 is provided to keep the paper down on the pins, this roller being kept away from enforcing a frictional contact of the paper with the pin wheels or the guard or guides 57, 58 by means of the ribs 41 on the 95 pin wheel bodies.

The record storage device is adapted to take one or more but preferably but one, of the webs of paper and wind it tightly and neatly on a roll supported above the platen. 100 This device comprises a roll 42, mounted on a removable shaft 43, set across an upright formation of the typewriter carriage.

The roll will preferably be provided with a rod or clip 42^a Figure 5, having a bent 105 end 42^b to seat in a terminal socket in the roll, thereby holding the paper steady on the roll in starting.

The roll is caused to revolve by a friction wheel 44, having a V-shaped convex 110 periphery, and suitably clutched to or secured to the roll. The friction wheel has also secured to it a ratchet wheel 45, which is engaged by a spring controlled lever 46, so as to be inhibited upon a forcing of the 115 lever in a direction opposed to its spring pull. As a preferred form of lever, I provide the bent arm 46, which has a pawl 47, hinged to it by a butte hinge. This pawl is pulled by a string 48 permitting it to give, 120 if it should strike the peak of a tooth of the ratchet 45, and is also pulled by a spring 49 which keeps the lever away from pawl contact.

On the end of the platen is a gear 50, 125 meshing with a large idler gear 51, which is mounted on the same pin as a carrying arm 52. This arm is spring impelled at 53, toward the rewind friction wheel, and carries a gear 54, meshing with the large gear in 130

all positions, this gear 54 carrying on its face a friction wheel 55, same having a V-shaped concave periphery to match with the convex periphery of the other friction wheel.

5 This rewind device acts to feed the rewind or record roll around in a frictional manner, and the inhibition of the movement of the roll, is accomplished by means of a pin or stud or roller 56 on the face 10 of the gear 50, said element contacting with the lower end of the lever 46 and forcing it to lock the record roll against movement. I accomplish by this mechanism, which is 15 geared to revolve the storage roll faster than the platen, a very tight and even roll, due to the well devised friction and the inhibition, which permits a looseness to accumulate and then be snapped up with a jerk. I also free the record web or strip 20 from strain at various intervals of its feed, so that it will have a chance to be aligned by the platen pin wheels, when in a loose condition.

As so far described the operation of my 25 machine is as follow:—The operator first loads the racks in the storage frame with suitable rolls of paper, and brings the separate webs up and over the idler rolls set at the top of said storage frame. The carbon 30 rolls are then put in place, and sufficient paper pulled out to reach to the printing point on the typewriter platen. The webs of paper are then passed between the carbon paper rolls, set over the idlers at the ends of 35 said rolls, and brought down to the platen where they are carefully aligned and set over the pins at the platen ends.

Before feeding the paper and writing thereon, the operator forms the loop D by 40 drawing sufficient paper off of the storage rolls, and then setting the various webs over the pins of the loop feeding pin wheels. Or he may free the webs from the platen pin wheels and revolve the platen shaft 45 manually, in the usual manner for typewriters, which will cause the loop feeding devices to accumulate the desired loop.

In any instance the alignment at the printing point is the necessary one, and the 50 webs will not align at the unwinding or loop feeding pin wheels, as the under sheets of loop are engaged to hang further than the upper sheets giving that freedom of relative movement necessary for aligning action upon them. In setting up the paper it is accordingly drawn with the films in progressively out of longitudinal alignment at the loop feeding point.

The usual operation of the machine as a 60 typewriter will cause a feeding of the various webs in alignment with each other, said webs being free of frictional strains because of the loop, and particularly the carriage and platen being free to move to and fro 65 past the printing point, because of the

freedom allowed by the loop. Also, since the unwinding or loop feeding pin wheels operate simultaneously with the platen pin wheels, they may be readily made to feed the paper off the storage rolls at the same 70 speed as it is fed past the printing point, whereby the same amount of paper will always remain in the loop.

I wish to note that whereas the pin wheel devices above described are all in pairs, operating on opposed margins of paper webs, that the machine will operate properly with but one sprocket instead of pairs in each instance and also that other forms of alignment devices could be used together with 80 the typewriter, such as, for example, that shown in my application, Serial No. 161,940, filed April 14th, 1917.

Also the exact nature of the means for 85 passing the webs of paper around the printing platen is not insisted upon, there being a number of ways hitherto devised by me and made subject of applications for patent covering devices for preventing the platen from actually feeding the strips and providing a loose or free engagement of the marginal holes of the paper with the pin wheels, such as shown in my pending application Serial No. 340,922.

As shown in Figures 10 and 11 of the 90 present drawings, this feature includes a pair of curved plates 57, 58, mounted on rods 57^a and 58^a. The plates are both slotted as at 59, for clearance of the feeding pins and guide the paper sheets to a substantially 100 tangential printing point. The plate 57 terminates below the printing point and the plate 58 extends above it to serve as a stripper and is cut away at the center to expose the platen to the papers as at 59^a.

In addition to the mechanism hitherto described, I may when desirable employ an automatic mechanism to provide for a regulated renewal of carbon paper, during the operation of the machine. Since carbon 110 paper varies in quality, and the operator of a machine also varies in touch, it is found necessary to renew carbon paper at varying stages of its use so that any one distinct period of renewal would not be satisfactory. 115

In the mechanism to be described I provide a means at regulated intervals for pressing firmly together the films of paper and the carbon paper, against the printing platen, which pressure or friction causes 120 the carbon paper to travel with the films of paper upon operation of the line spacer of a typewriter.

The mechanism is shown in Figures 12-17 and has been omitted for the sake of clearness from the machine shown in the balance of the views.

Both of the plates 57 and 58 which, as has been noted, act as a guide for the paper around the platen, are cut away at 60, at sev- 125 130

eral points so as to expose the platen, the preference being to have a number of cuts 60 rather than a single wide one, for retaining as much strength as possible in the 5 guide plates and to keep the paper away from the platen.

A series of pressure rollers 61 are provided, mounted on a shaft 62 carried on a plurality of arms 63. The shaft 62 also is 10 carried at one end by the end of the part 64 of a telescoping arm, having a part 65 and an intervening spring 66^a. The arm is mounted on a shaft 66, that is controlled by a lever 67.

15 The lever 67 is adapted for hand operation and is operated by a bell crank lever 68 mounted on the typewriter carriage and pivoted to the lever 67 at 69. By rocking the bell crank lever 68, manually, a clamping 20 of the paper on the pins will be accomplished. This operation is ordinarily intended for use in holding down the paper while tearing off, as will be noted, and it is not interfered with by the arm 65 to 25 extension of the spring 66^a.

On the shaft 66 is also an arm 70 under control of a spring 71, which is not as strong as the spring 66^a in the telescoping arm device. This spring 71 tends to draw the shaft 30 66 into a position to bring the rollers into contact with the platen.

For automatic operation the telescoping arm has on its end 65, a roller 72, which 35 rides in a box cam 73, same having a cam flange with a notch therein into which the roller will move, under influence of the spring 71, thereby accomplishing a resilient extension movement of the rollers into frictional contact position. Some other arrangement of the cam and spring could accomplish the same result, as the above, but it is preferred by me since it is a fully 40 resilient movement, thereby providing an automatic take up for the thickness of paper on the platen, due to the number of webs of paper in use.

For operating the box cam it is mounted on a cross shaft 74 on the machine carriage 50 which is rotated by a ratchet 75. This ratchet wheel is operated by a pawl 76, spring pressed at 77, and controlled in its mesh with the ratchet by a stop 78. The stop operates as in a Underwood typewriter, 55 and is mounted on a slide fork 79 held and guided on cap screws 80. The position of the fork is controlled by a bell crank lever 81, which works over a segment 82, and has a pin at 83 to ride under a bifurcated portion 84 of the fork. This bell crank may 60 be loosely mounted over the shaft that mounts the box cam, and ratchet, and the position thereof controls as to whether the pawl moves one, two or three teeth of the 65 ratchet at a time.

For operating the pawl, a V-shaped lug 84 is mounted on some fixed portion of the typewriter, which lug contacts with the end of a bell crank 85, mounted on the carriage of the machine. The inner end of the bell 70 crank contacts with and thrusts over, when the carriage is moved transversely of the fixed body of the machine, a slide 86, having an antifriction roller 87, which slide is mounted in a guide plate or plates 88 on the carriage. The slide carries the spring 75 pressed pawl, for meshing with the ratchet and is itself held by a spring 89 in a retracted position.

The operator interleaves the carbon paper, 80 as noted above for manual operation, and operates his machine in the normal manner. Each passage of the carriage across the machine operates the pawl and turns the ratchet the desired number of notches. When the ratchet turns the box cam to a position for 85 permitting the forward contact and operation of the friction rollers, thereby bringing the films of paper and carbon paper frictionally together, the next following operation of the line spacer will carry along the carbon paper with the films of paper written upon, thus changing it at the printing line.

While the mechanism described for manually exercising friction may be employed 90 for use in advancing the carbon paper, which would be somewhat clumsy due to the necessity of holding it down while the line spacer is operated, its chief use is to hold the paper while it is being torn off of the machine.

I have shown as mounted on the supporting bars for the roller or bar 40, that holds the paper on the feed pins, a tear off knife 90, against which the films of paper may be torn whenever desired. During this tearing off the operator should press down on the bell crank lever 68 thereby holding the paper firmly against the platen and preventing its 100 shifting during the tearing operation.

It should be noted of the guard or guide plate 58 which comes up over the platen and acts as a stripper for the various films, that it is so designed as to afford a base or 105 resting place for the looseness or loop left in the record strip during the period of inhibition of the rewind device.

While I have shown a device for clamping the paper during tearing off and during the feed of the carbon paper, which frictionally engages the paper on the platen, I also desire to provide a special arrangement of the cross bar or roller which is employed for keeping the paper down on the pins.

A showing of this has been omitted from the various assembly views for purposes of simplicity and because a complete operative machine may be had without it. As shown in Figures 18, however, a special 125 130

form of cam is provided for the pin wheel feed devices on the typewriter platen which cam permits the roller or bar to come down on the paper sufficiently to hold it tightly 5 against the platen.

These cams which have been indicated at 80, have a series of notches 81 therein so placed as to coincide in position with the click of the line spacer of the typewriter platen. Since the roll, here noted 10 as 83, rests by spring tension on the cams, each time the typewriter platen comes to rest after a line spacing movement, the roller will be permitted to move into contact with the paper, thereby holding it 15 while being written upon. As soon as the line spacing feed, and hence a rotation of the platen, is set into motion, the roller will be lifted by the cams away from the 20 paper, and will relieve it for adjustment during the pin feed. By a proper proportioning of the notches the release of the pressure may be made for the desired number of line spacing movements.

25 By the use of this device I can do away with the hand operated clamping levers described as for use during tearing off, or merely use them for certain desired non-automatic feeding of the carbon paper. I 30 cannot employ this new device for carbon paper feed, however, since this carbon feed requires a release of pressure on the platen, while same is being revolved in a line spacing movement.

35 Various equivalent structures for accomplishing the objects of my invention, which will accomplish the various operations above described, will occur to the mechanic skilled in the art, and it is my desire that my invention be construed to cover such alternative structures, and that my claims be construed with the full benefit of the doctrine of equivalents.

Having thus described my invention, 45 what I claim as new and desire to secure by Letters Patent, is:—

1. In combination with a typewriter having a movable platen, a fixed frame for storage of paper, and means for feeding a 50 plurality of webs of paper continuously from the fixed frame to the platen so as to maintain an excess of paper between the same frame and platen said means acting on each web individually as distinguished 55 from acting on all webs as a group and comprising rotary pin bearing bodies to which the webs are guided so as not to wrap around said bodies, the paper having spaced feeding holes for the pins.

60 2. In combination with the typewriter having a movable platen, a fixed frame for storage of paper, and means for feeding a plurality of webs of paper continuously 65 from the fixed frame to the platen so as to maintain a loop of paper at all times be-

tween said frame and platen said means acting on each web individually as distinguished from acting on all webs as a group and comprising rotary pin bearing bodies to which the webs are guided so as not to wrap around 70 said bodies, the paper having spaced feeding holes for the pins.

3. In combination with a typewriter having a platen, means for feeding paper around said platen, means for storing a supply of continuous webs of paper, means for feeding said webs of paper from the supply, said two means for feeding said webs adapted for simultaneous and continuous 80 operation and last named means acting on each web individually as distinguished from acting on all webs as a group and comprising rotary pin bearing bodies to which the webs are guided so as not to wrap around 85 said bodies, the paper having spaced feeding holes for the pins.

4. In combination with a typewriter having a fixed frame, a movable carriage and platen in said frame, a fixed storage frame 90 for storage of continuous webs of paper, and means operated from the platen for feeding the paper webs from the storage frame, and for feeding the strips past the said platen, whereby an excess of paper 95 may be maintained between said two feeding device to permit carriage movement said means acting on each web individually as distinguished from acting on all webs as a group and comprising rotary pin bearing bodies to which the webs are guided so 100 as not to wrap around said bodies, the paper having spaced feeding holes for the pins.

5. In a machine for making multiple copies, means for storing a plurality of continuous webs of paper, a platen for the webs of paper at a point for receiving impressions, means for feeding the webs of paper past said platen, and additional means for feeding the webs of paper from the storing means whereby looseness of 110 paper is provided for, with relation to the first mentioned feeding means and said last named means acting on each web individually as distinguished from acting on all webs as a group and comprising rotary pin bearing bodies to which the webs are guided so as not to wrap around 115 said bodies, the paper having spaced feeding holes for the pins.

6. In a machine for making multiple copies, means for storing a plurality of continuous webs of paper, a platen for the webs of paper at a point for receiving impressions, means for feeding the webs of paper past said platen, additional means for feeding the webs of paper from the storing means, said two feeding means being operably connected to each other for co-incident operation and said last named means acting on each web individually as distinguished from acting on all webs as a group 125

- and comprising rotary pin bearing bodies to which the webs are guided so as not to wrap around said bodies, the paper having spaced feeding holes for the pins.
- 5 7. The combination with a typewriting machine having a movable platen of mechanism adapted to feed to said platen, a loose series of paper webs, said mechanism adapted to feed each individual web by individual engagement therewith and comprising rotary pin bearing bodies to which the webs are guided so as not to wrap around said bodies, the paper having spaced feeding holes for the pins.
- 10 8. The combination with a typewriting machine having a movable platen of mechanism adapted to feed to said platen a loose series of paper webs, said mechanism being operably connected to the platen for co-incident operation therewith, and said mechanism adapted to feed each individual web by individual engagement therewith, and comprising rotary pin bearing bodies to which the webs are guided so as not to wrap around said bodies, the paper having spaced feeding holes for the pins.
- 15 9. The combination with a typewriting machine having a movable platen of mechanism adapted to feed to said platen a loose series of paper webs, said mechanism being stationary with relation to the typewriting machine, and said mechanism adapted to feed each individual web by individual engagement therewith, and comprising rotary pin bearing bodies to which the webs are guided so as not to wrap around said bodies, the paper having spaced feeding holes for the pins.
- 20 10. In a machine for making multiple copies on continuous webs of paper having holes arranged successively therein, the combination of a typewriter frame, and a paper supply frame fixedly related to the typewriter frame, a movable platen carrier on said typewriter frame, and pin bearing bodies for feeding of paper past said platen, and additional pin bearing bodies for feeding paper out of said storage frame, said bodies being connected together for the purpose described and the paper being led to the additional bodies so as not to wrap around said bodies.
- 25 11. The combination with a movable platen carrier for typewriters of a fixed frame for storage of a plurality of webs of paper, and feeding means for the paper adapted to form loops of paper adjacent the carrier to permit its movement with relation to the storage means, said means being adapted to preserve each loop in a constant relation.
- 30 12. In a machine for making multiple copies on continuous webs of paper having holes successively arranged therein, the combination of pin bearing bodies for feeding the paper webs past an impression or printing point, additional pin bearing bodies for feeding the paper prior to its engagement by the pin bearing bodies first mentioned, said two pin bearing bodies being connected for joint operation, whereby a loose arrangement of paper may be maintained between said two feeding bodies and the paper being led to the additional bodies so as not to wrap around said bodies.
- 35 13. The combination with a typewriting machine having a movable platen of a means for providing continuous webs of paper to said typewriting machine comprising a storage frame for multiple webs of paper and pin bearing bodies mounted in said frame and adapted to engage holes in said webs of paper, said webs being led in substantially horizontally planes to the pin bearing bodies and operative connection to said pin bearing bodies from the typewriter mechanism, for the purpose described.
- 40 14. In a machine for making multiple copies on continuous webs of paper, the combination with a movable platen, of means movable therewith for laterally aligning of various webs of paper, and means also movable therewith for longitudinally aligning said webs, and paper feeding means adapted to continuously deliver to the said aligning means a loose body of paper.
- 45 15. In a machine for making multiple copies on continuous webs of paper, the combination with a movable platen, of means movable therewith for laterally aligning of various webs of paper, and means for longitudinally aligning said webs, and paper feeding means adapted to continuously deliver to the said aligning means a loose body of paper in the form of a loop, whereby the said movable parts shall be free for movement with relation to the paper feeding means.
- 50 16. In a device of the character described a lateral aligning means and carbon paper holder, comprising a series of carbon paper rolls, one for each copy to be made, and idler pin bearing bodies mounted axially of said rolls, and adapted to engage in successive holes formed in a series of webs of paper.
- 55 17. In a device of the character described a lateral aligning means and carbon paper holder comprising a series of carbon paper rolls, one for each copy to be made, idler pin bearing bodies mounted axially of said rolls, and adapted to engage successive holes formed in a series of webs of paper, and means for guiding such webs of paper over the said carbon paper rolls free of frictional contact therewith.
- 60 18. The combination with a typewriting machine having a movable platen of mechanism adapted to feed to said platen a loose series of paper webs, and pin bearing bodies

- for aligning and pin bearing bodies for feeding said paper webs by engagement in successive holes formed therein engaging the webs prior to reaching the platen.
- 5 19. In a machine for laterally aligning and longitudinally aligning of a multiple series of webs of paper to be printed upon in superimposed and aligned condition, the combination with a movable platen carrier, of pin bearing bodies adapted to engage successive holes formed in the paper webs for feeding and longitudinal alignment, and idler pin bearing bodies adapted to engage said holes for lateral alignment.
- 10 20. In a machine for laterally aligning and longitudinally aligning of a multiple series of webs of paper to be printed upon in superimposed and aligned condition, the combination with a movable platen carrier, of pin bearing bodies adapted to engage successive holes formed in the paper webs, for feeding and longitudinal alignment, and idler pin bearing bodies adapted to engage said holes for lateral alignment, and means 25 for loosely but positively feeding to said machine of webs of paper at the feeding rate of the first mentioned pin bearing bodies.
- 15 21. A mechanism for laterally aligning and interlacing carbon paper between a plurality of webs of paper comprising a spring pintle element, a rotary pin bearing body on said pintle element and rotatable idly thereon, and a carbon paper roll frictionally engaged by said spring pintle element.
- 20 22. In a typewriting machine having a rotatable platen, the combination with means for feeding paper past said platen, of means for rolling up said paper after passing said platen, comprising a rotatable body, frictional means for driving the same operably connected with the platen for simultaneous operation therewith, and means for inhibiting the operation of said frictional means during a portion of the movement of the platen.
- 25 23. In a typewriting machine the combination with a platen, of means for feeding continuous webs of paper past said platen, said means comprising rotary pin bearing bodies adapted to engage successive holes in the paper, and a record rewind device comprising a rotary body, frictional means for driving it simultaneously with the platen, and means for inhibiting the operation of the frictional means during a portion of the operation of the paper feeding means.
- 30 24. In a typewriting machine the combination with a movable platen, of means for feeding continuous webs of paper past said platen, said means comprising rotary pin bearing bodies adapted to engage successive holes in said paper, a record rewind device comprising a rotary body, means for driving it simultaneously with the paper feeding device, means for driving the paper feeding device simultaneously with the movement of the platen and means for inhibiting the operation of the rotary rewind body during a portion of the operation of the rewind device.
- 35 25. In combination with a typewriter having a fixed frame and a movable carriage a fixed storage frame for storage of continuous webs of paper, means for feeding the paper in the movable carriage, and means for feeding paper simultaneously from the fixed frame to the movable carriage whereby a loop is formed and maintained between the fixed frame and the carriage, a measured feed being imparted by the latter means, said loop having the lower films of paper of substantially greater length than the loops above them whereby friction between the films of the loop is avoided.
- 40 26. In combination with a typewriter having a movable carriage, means on the carriage for feeding a plurality of films of paper in alignment with each other comprising one or more pin bearing bodies adapted to engage upon rotation in successive holes formed similarly in the various films of paper, a fixed paper supply element, means for feeding paper from the paper supply element in measured lengths and simultaneously with the first mentioned feed so as to automatically maintain a loop of paper between the carriage and the supply element, with the paper initially arranged between the supply element and the carriage in a loop in which each film therein extends substantially lower than the films above it, whereby each film is free from frictional engagement with the others in the loop.
- 45 27. In a typewriting machine having a rotatable platen the combination with means for feeding a plurality of webs of paper past said platen, of means for rolling up one of said webs of paper after passing said platen comprising a rotatable body, and frictional driving means for the same, operably connected with the platen.
- 50 28. In a typewriting machine the combination with a platen of means for feeding continuous webs of paper past said platen, said means comprising rotary pin bearing bodies adapted to engage successively holes in the paper, and a record re-wind device for one of the webs comprising a rotary body, and frictional means for driving it simultaneously with the platen.
- 55 29. In a typewriting machine the combination with a movable platen of means for feeding continuous webs of paper past said platen, said means comprising rotary pin bearing bodies adapted to engage success-

sive holes in said paper, a record rewind device for one of the webs comprising a rotary body, means for driving it simultaneously with the paper feeding device, and 5 means for driving the paper feeding device simultaneously with the movement of the platen.

30. In a device of the character described the combination with a rotary platen, 10 a typewriter carriage upon which the same is mounted, rotary pin bearing bodies associated with the platen for feeding a plurality of webs of paper past the platen, and a movable frame having a bar associated 15 with the pin bearing bodies and adapted to retain the paper thereon without friction, said bar having associated therewith a knife against which the films of paper may be torn off.

20. 31. In a device of the character described a typewriter carriage means for feeding a plurality of webs of paper past the printing point on said carriage comprising rotary pin bearing bodies adapted to engage successive holes in the webs of paper, means 25 for guiding the webs of paper in a substantially tangential path with relation to the rotary pin bearing bodies, and a movable frame having a bar associated with the rotary pin bearing bodies and provided with clearance slots adapted to maintain the webs of paper on the pins thereof without friction and means fixedly mounted in connection with said movable frame having a 30 knife edge for tearing off the webs of paper.

32. In a manifolding typewriter, the combination with a carriage, a rotary platen, pins arranged axially of the platen and 40 adapted to engage successive holes in a plurality of webs of paper, guide plates for directing the paper in substantially a tangential path with relation to the platen, a bar or the like to maintain the paper on the 45 said pins, and a fixed tear off knife associated with the bar whereby the webs of paper may be torn off below the portion thereof upon which writing has been made.

33. In a manifolding machine the combination with rotary pin bearing bodies 50 mounted axially of the rotary platen of a typewriter carriage, of a tear off bar located adjacent the level of the said platen.

34. In a manifolding machine the combination with rotary pin bearing bodies 55 mounted axially of the rotary platen of a typewriter carriage, of a tear off bar located adjacent the level of the said platen, said tear off bar having associated there- 60 with a groove bar adapted to rest over the pin bearing bodies and retain webs of paper thereon.

35. In a device of the character described a lateral aligning means and carbon paper 65 holder comprising members over which

webs of paper may pass to engage the paper so as to confine them laterally and carbon paper rolls mounted together with said members, one for each copy to be made.

36. In a device of the character described 70 a carbon paper interleaver comprising a frame, a series of rolls of carbon paper mounted in said frame, and means for passing webs of paper individually over said carbon paper rolls without frictional contact therewith, same comprising rotary elements on the ends of the carbon paper rolls, and guards extending over the said rolls.

37. In a machine of the character described, the combination with a movable 80 typewriter carriage, a fixed paper supply element, feeding means for paper to maintain a loop thereof between the supply element and the carriage, and an upwardly open housing or cabinet built up around 85 the space intermediate the paper supply element and coming substantially to the level of the carriage to protect the said paper loop, said typewriter carriage having extending elements thereon lying across the opening to the cabinet to guard the side edges of the paper loop as it emerges from 90 said cabinet.

38. In a manifolding machine the combination with rotary pin bearing bodies 95 mounted axially of the rotary platen of a typewriter carriage, of a tear off bar associated with said carriage, means for loosely retaining paper sheets for feeding engagement by the pin bearing bodies, and a 100 clamping device for retaining webs of paper frictionally against the platen while being torn off, said clamping device being retainable in nonclamping position.

39. In a manifolding machine the combination with a rotary platen on a typewriter carriage, means for passing a plurality of webs of paper around said platen, a tear off knife associated with the platen, and means for clamping the plurality of webs 110 of paper against the platen while being torn off, said means being retainable in nonclamping position.

40. In a manifolding machine the combination with a rotary platen on a typewriter 115 carriage, means for passing a plurality of webs of paper around said platen, a tear off knife associated with the platen, and means for clamping the plurality of webs of paper against the platen while being torn off, said 120 means comprising friction elements and means for pressing them against the platen and means for retaining them away from the platen.

41. In a manifolding machine the combination with a rotary platen on a typewriter carriage, means for passing a plurality of webs of paper around said platen, a tear off knife associated with the platen, and means for clamping the plurality of webs 125 130 of paper against the platen while being torn off, said means comprising friction elements and means for pressing them against the platen and means for retaining them away from the platen.

of paper against the platen while being torn off, said means being adapted to contact with the platen at a point below the printing point thereon and having means to retain it away from the platen.

42. In a manifolding machine the combination with rotary pin bearing bodies mounted axially of the rotary platen of a typewriter carriage, of a tear off bar associated with said carriage, means for loosely retaining paper sheets for feeding engagement by the pin bearing bodies, and a clamping device for retaining webs of paper frictionally against the platen while being torn off, said means being adapted to contact with the platen at a point below the printing point thereon and having means to retain it away from the platen.

43. In a manifolding machine the combination with rotary pin bearing bodies mounted axially of the rotary platen of a typewriter carriage, of a tear off bar associated with said carriage, means for loosely retaining paper sheets for feeding engagement by the pin bearing bodies, and a clamping device for retaining webs of paper frictionally against the platen while being torn off, said means for loosely retaining the paper sheets comprising guides positioned around the under side of the platen so as to lead the paper in a substantially tangential path past the printing point on the platen, and said clamping device being adapted to extend through openings in said guides so as to clamp the paper to the platen below the printing point thereof.

44. In a machine of the character described the combination with a means for feeding a plurality of webs of paper past a rotary platen without friction thereagainst, of means for retaining carbon paper sheets between said webs of paper so as not to feed therewith when under friction and means for mechanically applying friction to the papers against the platen whereby the carbon paper will feed with the plural webs.

45. In a machine of the character described the combination with a means for feeding a plurality of webs of paper past a rotary platen without friction thereagainst of means for retaining carbon paper sheets between said webs of paper so as not to feed therewith when under friction and means for mechanically applying friction to the papers against the platen whereby the carbon paper will feed with the plural webs, said means comprising elements movable into contact with the platen below the printing point thereon.

46. In a machine of the character described the combination with a means for feeding a plurality of webs of paper past a rotary platen without friction thereagainst of means for retaining carbon paper sheets

between said webs of paper so as not to feed therewith when under friction and means for mechanically applying friction to the papers against the platen whereby the carbon paper will feed with the plural webs, and automatic means for periodically operating said friction applying means.

47. In a machine of the character described the combination with a means for feeding a plurality of webs of paper past a rotary platen without friction thereagainst of means for retaining carbon paper sheets between said webs of paper so as not to feed therewith when under friction and means for mechanically applying friction to the papers against the platen whereby the carbon paper will feed with the plural webs, and automatic means for periodically operating said friction applying means, 80 said automatic means being adjustable for controlling the periodicity of said operations.

48. In a manifolding typewriter, the combination with means for printing on and feeding a plurality of webs of paper without frictional grasp on the webs thereof, means for supplying interleaved webs of carbon paper between the webs to be written upon and extending in the direction of the webs, and means for automatically renewing fresh portions of carbon paper to the printing point.

49. In a manifolding typewriter, the combination with means for printing on and feeding a plurality of webs of paper without frictional grasp on the webs thereof, means for supplying interleaved webs of carbon paper between the webs to be written upon and extending in the direction of the webs, and means for automatically renewing fresh portions of carbon paper to the printing point, at interspaced periods of the printing operation.

50. In a manifolding typewriter, the combination with means for printing on and feeding a plurality of webs of paper without frictional grasp on the webs thereof, means for supplying interleaved webs of carbon paper between the webs to be written upon and extending in the direction of the webs, and means for automatically renewing fresh portions of carbon paper to the printing point, at adjustably optional periods of the printing operation.

51. In a manifolding typewriter, the combination with a movable carriage therefor, means for printing on and feeding a plurality of webs of paper, means for supplying interleaved carbon paper between the webs of paper to be written upon and extending in the direction of the webs, means for automatically renewing fresh portions of carbon paper to the printing point, said means being adapted to operate to move the carbon paper at intervals, and adjustable to op-

erate at each line spacing operation of the platen or at intermittent line spacing movements.

52. In a manifolding typewriter, the combination with a movable carriage therefor, means for printing on and feeding a plurality of webs of paper, means for supplying interleaved carbon paper between the webs of paper to be written upon and extending in the direction of the webs, means for automatically renewing fresh portions of carbon paper to the printing point, said means being operably connected to the movable carriage to be energized thereby at selected points in the carriage movement.

53. In a manifolding typewriter, the combination with a movable carriage therefor, means for printing on and feeding a plurality of webs of paper, means for supplying interleaved carbon paper between the webs of paper to be written upon and extending in the direction of the webs, means for automatically renewing fresh portions of carbon paper to the printing point, said means being operably connected to the movable carriage to be energized at each selected movement thereof and adjustably intermittently with a plurality of movements.

54. In a manifolding typewriter, the combination with means for printing on and feeding a plurality of webs of paper, means for supplying interleaved carbon paper between the webs to be written upon, a rotary platen for the typewriter, a movable carriage for the typewriter, means for holding the carbon paper against normal movement with the movements of the platen, and means for feeding the carbon paper together with the platen once for a selected number of carriage movements.

55. In a manifolding typewriter, the combination with means for printing on and feeding a plurality of webs of paper, means for supplying interleaved carbon paper between the webs to be written upon, a rotary platen for the typewriter, a movable carriage for the typewriter, means for holding the carbon paper against normal movement with the movements of the platen, and means for feeding the carbon paper together with the platen once for a selected number of carriage movements, said means being interconnected with the movable carriage and adapted to set by a selected carriage movement.

56. In a manifolding typewriter, the combination with means for printing on and feeding a plurality of webs of paper, means for supplying interleaved carbon paper between the webs to be written upon, a rotary platen for the typewriter, a movable carriage for the typewriter, means for holding the carbon paper against normal movement with the movements of the platen, and means for feeding the carbon paper together

with the platen at selected intervals, said means comprising a friction device applicable to the platen, cam means for setting the said device, continued means for operating the cam means from the platen operation, 70 and means for operating the friction device from the carriage motion.

57. In a manifolding typewriter, the combination with means for printing on and feeding a plurality of webs of paper, means 75 for supplying interleaved carbon paper between the webs to be written upon, a rotary platen for the typewriter, a movable carriage for the typewriter, means for holding the carbon paper against normal movement 80 with the movements of the platen, and means for feeding the carbon paper together with the platen at selected intervals, said means comprising a friction device applicable to the platen, cam means for setting the 85 said device, a pawl and ratchet for setting the cam, means operable from the platen for actuating the pawl and ratchet, and means operable from the carriage movement for moving the friction device into contact position.

58. In a manifolding typewriter, the combination with means for printing on and feeding a plurality of webs of paper, means 90 for supplying interleaved carbon paper between the webs to be written upon, a rotary platen for the typewriter, a movable carriage for the typewriter, means for holding the carbon paper against normal movement 95 with the movements of the platen, and means for feeding the carbon paper together with the platen at selected intervals, said means comprising a friction device applicable to the platen, and mechanism operated from the carriage for throwing it into operation and 100 separate means manually operable for setting said friction device into friction position.

59. In a manifolding typewriter machine, the combination with means for engaging 110 holes formed in a plurality of webs of paper and feeding the paper by means of said engagement, means for supplying paper to said engaging means in a loose condition whereby the webs may adjust themselves on 115 the pins during the feed, and a paper clamping means to hold it while being written upon, and mechanism connected to the hole engaging means for providing the release of the clamping means at every feeding movement of a line spacing character, and permitting its clamping engagement at pauses in the feed.

60. In a manifolding typewriter machine, the combination with a platen against which 120 writing may be done, a movable typewriter carriage, movable toothed means for feeding a plurality of webs of paper having holes therein to be engaged by the teeth, means to press the paper against the platen, said 125

toothed means having a step-by-step movement, and means for inhibiting the means for pressing the paper on the platen, timed with relation to said step-by-step movement.

5 61. In combination with a typewriter having a movable carriage and a platen on said carriage, toothed means for feeding a plurality of webs of paper past a printing point on said platen, said webs of paper 10 having holes therein for engagement by said toothed means, said toothed means having a step-by-step movement as a line spacer, a mechanism for pressing the paper against the platen timed with relation to said step-by-step line spacing movement, whereby it 15 will press the paper at pauses in the said movement and release it for loose feeding intermediate said stops.

62. In a device of the character described, 20 the combination of a carriage, a rotary platen thereon, toothed means on the platen for engaging suitable holes in a plurality of webs of paper, means for pressing the paper against the platen, said platen having a line 25 spacing step-by-step movement, and means controlled by said platen movement to release the pressing means during said step-by-step movements.

63. In a device of the character described, 30 the combination of a carriage, a rotary platen thereon, toothed means on the platen for engaging suitable holes in a plurality of webs of paper, means for pressing the paper against the platen, means for directing the 35 path of the paper so as to be tangential and hence nonbinding with relation to the platen, said platen having a step-by-step line spacing movement, and means controlled by said platen movement to release the pressing 40 means during said step-by-step movements.

64. In a device of the character described, the combination of a carriage, a rotary platen thereon, toothed means on the platen for engaging suitable holes in a plurality of 45 webs of paper, means for pressing the paper against the platen, means for directing the path of the paper so as to be tangential and hence nonbinding with relation to the platen, said platen having a step-by-step 50 line spacing movement, and means controlled by said platen movement to release the pressing means during each individual step-by-step movement.

65. In a device of the character described, 55 the combination of a typewriting machine having a movable carriage and a platen thereon, toothed means on the platen for feeding a plurality of webs of paper by engagement with suitable holes formed in said paper, a pressure roller for pressing the paper against the platen, contact means for the roller adapted to raise it from pressing position and lower it thereto, said means 60 being arranged in a step-by-step movement

to correspond to a line spacing movement of 65 the toothed feeding means.

66. In a manifolding typewriter machine, the combination with a platen against which printing may be done, a typewriting device, movable toothed means for feeding 70 a plurality of webs of paper having holes therein to be engaged by the teeth, means to press the paper against the platen, and a step-by-step mechanism arranged to correspond to a line spacing movement of the 75 paper, said mechanism being under control of the toothed means, and adapted to enforce a release of pressure during each movement of a line spacing character.

67. A mechanism for laterally aligning 80 and interlacing carbon paper in a device of the character described comprising a pintle element, a pair of idler pin bearing members on said element, and a carbon paper roll on said pintle intermediate the idler 85 members.

68. Means for maintaining a plurality of webs of paper against a rotary platen during printing operations, said platen having a step-by-step line spacing movement, comprising a presser element to contact with the webs, and means controlled by said step-by-step movement for releasing the contact of said element during the platen rotation.

69. Means for maintaining a plurality of webs of paper against a rotary platen during printing operations comprising a presser element to contact with the webs, and means operatively connected with the platen for 100 releasing the contact of said element during platen rotation.

70. In a manifolding typewriter machine, the combination with a rotary platen against which writing may be done, means for feeding in loose condition a plurality of webs of paper by said platen, means for pressing the paper against the platen, and means operatively connected with the platen to release the pressing means during platen 105 movement.

71. In a manifolding typewriter machine, the combination with a rotary platen against which writing may be done, said platen having a step-by-step line spacing movement, means for feeding in loose condition a plurality of webs of paper by said platen, means for pressing the paper against the platen, and means operatively connected 115 with the platen to release the pressing means during platen movement.

72. In combination with a typewriter having a movable carriage and platen on said carriage, toothed means for feeding a plurality of webs of paper past a printing point on said platen, said webs of paper having holes therein for engagement by said toothed means, mechanism for pressing 125

the paper against the platen, and interconnecting mechanism intermediate the toothed means and the pressing mechanism to release the latter during movements of the former.

73. In a device of the character described, the combination of a carriage, a rotary platen thereon, toothed means on the platen for engaging suitable holes in a plurality of webs of paper, means for pressing the

paper against the platen, means for directing the path of the paper so as to be tangential and hence nonbinding with relation to the platen, said platen having a rotary line spacing movement, and means controlled by said platen movement to release the pressing means during said rotary movements.

15.

JOHN Q. SHERMAN.
